RAILWAY TRAFFIC CONTROLLING APPARATUS

Filed April 30, 1926

UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 30, 1926. Serial No. 105,763.

My invention relates to railway traffic controlling apparatus, and particularly to apparatus of the type wherein train carried governing means is controlled by currents flowing in the trackway. More particularly my present invention relates to the trackway portion of such apparatus.

I will describe one form of trackway apparatus embodying my invention, and will then point out the novel features thereof in claims.

The accompanying drawing is a diagrammatic view illustrating one form of trackway apparatus embodying my invention.

Referring to the drawing, the reference characters 1 and 1^a designate the track rails of a stretch of railway track over which traffic moves in both directions. These rails are divided, by means of insulated joints 2, into a plurality of successive track sections, A—B, B—C, etc. Each track section is provided with a track relay designated by the reference character R with a distinguishing exponent and comprising two windings 7 and 8. Winding 7 of each track relay R is constantly connected across the right-hand end of the associated section, and winding 8 of each relay R is constantly supplied with alternating current from a suitable source such as secondary 15 of an associated line transformer designated by the reference character L with an appropriate distinguishing exponent. The primary 16 of each line transformer L is constantly supplied with alternating current from alternator M, over line wires 3 and 3^a. Referring particularly to relay R^B, the circuit for winding 8 of this relay may be traced from secondary 15 of transformer L^B, through wires 17, 18 and 19, winding 8 of relay R^B and wires 20, 21, 22, 23 and 23^a, back to secondary 15 of transformer L^B.

Each track section is normally supplied with alternating track circuit current from a track transformer designated by the reference character K with a suitable distinguishing exponent. The secondary 10 of each transformer K is constantly connected across the rails adjacent the left-hand end of the associated section in series with an impedance 9. The supply of alternating cur-

rent to the primary 11 of each transformer K will be described in detail hereinafter.

Each track section is further provided with a second transformer designated by the reference character G with a suitable exponent and having a secondary winding 13 connected across the rails adjacent the right-hand end of the associated section in series with an impedance 12 and back contact 39 of the track relay R for the same section. It is manifest therefore that secondary 13 of each transformer G is connected with the rails of the corresponding section when and only when the track relay R for the same section is deenergized. Primary 14 of each transformer G is at times supplied with alternating current as will appear hereinafter.

Located adjacent the left-hand end of each track section is a control relay designated by the reference character P with an exponent corresponding to the location. A similar control relay designated by the reference character Q with an appropriate exponent is located adjacent the right-hand end of each track section. The control relays P and Q for each track section are controlled by the track relay R for such section. Referring, for example, to section A—B the circuit for relay P^A may be traced from secondary 15 of transformer L^B, through wires 17 and 24, back contact 25 of relay R^B, wires 26, 26^a and 27, winding of relay P^A, wire 28, back contact 29 of relay P^A, and wires 30, 31, 32, 33 and 23^a back to secondary 15 of transformer L^B. The circuit for relay Q^B passes from secondary 15 of transformer L^B through wires 17 and 24, back contact 25 of relay R^B, wires 26, 26^a and 34, winding of relay Q^B, wire 35, back contact 36 of relay Q^B, and wires 37, 38, 23 and 23^a, back to secondary 15 of transformer L^B. It will be seen that the circuit for each of the control relays P and Q includes its own back contact and a back contact of the track relay for the associated section. When the track relay is energized, therefore, both of the control relays are de-energized. When the track relay is de-energized, however, the circuits will be closed for the control relays and the circuit for each control relay includes a back contact thereof. The control relays will

then both become energized. The opening of their back contacts will open their circuits and the control relays will then again open. It follows that as long as the track relay 5 remains in its de-energized condition, the control relays will operate intermittently, opening and closing their back contacts.

Traffic through the stretch of track shown in the drawing is controlled by a plurality 10 of governing devices here shown as track-way signals each designated by the reference character S with a distinguishing exponent and each capable of indicating proceed, caution or stop. Signals S², S⁴ and S⁶ located at points C, B and A, respectively, 15 govern westbound traffic, that is, traffic moving from right to left. Signals S¹, S³ and S⁵ govern eastbound traffic, that is, traffic moving from left to right. The signals S are controlled in accordance with any of the 20 well known systems of single track signaling. The means for controlling these signals forms no part of my present invention and is omitted from the drawing for the sake of simplicity. For purposes of explanation I will assume that the signals form a 25 part of an absolute permissive block signaling system so that the signals all normally indicate proceed. When a section is occupied by a train moving in one direction the signals in advance of said train which govern traffic in the opposite direction indicate stop. Furthermore, the signals which govern traffic in the direction in which the train 30 is moving are so controlled that the signal associated with the occupied section indicates stop, and the signal associated with the section next in rear of the occupied section indicates caution. Associated with each signal S is a circuit controller designated by 35 the reference character D with an exponent corresponding to the location and arranged to close contact 4-5 when the signal indicates proceed or caution, but to close contact 4-6 when such signal indicates stop.

The primary 11 of transformer K^A is provided with one circuit which may be traced from secondary 15 of transformer L^A, through wires 40 and 41, contact 4-6 of circuit controller D⁶, wire 48, primary 11 of transformer K^A and wires 45, 47, 32 and 32^a back to secondary 15 of transformer L^A. This circuit is closed only when signal S⁶ indicates stop, under which condition uninterrupted alternating current is supplied to primary 11 of transformer K^A. When signal S⁶ indicates proceed or caution, the circuit just traced is opened and a second circuit is closed for primary 11 over which current 50 flows from secondary 15 of transformer L^A, through wires 40 and 41, contact 4-5 of circuit controller D⁶, wire 42, back contact 43 of relay P^A, wire 44, primary 11 of transformer K^A, and wires 45, 47, 32 and 32^a back 55 to secondary 15 of transformer L^A. When

this circuit is closed, and relay P^A is de-energized, uninterrupted alternating current is supplied to primary 11. If, however, relay P^A is being operated to alternately open and close its back contact 43, the circuit just traced will be intermittently closed so that the alternating current supplied to primary 11 of transformer K^A will be regularly interrupted.

The primary 11 of each of the remaining 75 transformers K is provided with circuits similar to those just described for transformer K^A.

Primary 14 of transformer G^B is provided with a circuit which may be traced from secondary 15 of transformer L^B, through wires 17 and 24, back contact 25 of relay R^B, wires 26 and 56, contact 4-5 of circuit controller D³, wire 51, back contact 52 of relay Q^B, wire 53, primary 14 of transformer G^B, and wires 80 55, 21, 22, 23 and 23 back to secondary 15 of transformer L^B. With signal S³ indicating caution or proceed, if relay R^B is de-energized, secondary 13 of transformer G^B is connected with the rails of section A-B, 85 relay Q^B will be intermittently operated as explained hereinbefore, and alternating current will be supplied to primary 14 of transformer G^B over the circuit just traced. But the operation of relay Q^B will alternately 90 open and close this circuit so that the alternating current supplied to the rails of section A-B is regularly interrupted.

When signal S³ is at stop however, the circuit just traced is interrupted and no current is supplied to the rails of section A-B by transformer G^B.

Each of the remaining transformers G is provided with circuits similar to those just described for transformer G^B.

As shown in the drawing the stretch of track is unoccupied so that signals S all indicate proceed. Uninterrupted alternating current is therefore supplied to the primary 11 of each transformer K. The track relay R for each section is therefore energized so that the primary 13 of each transformer G is disconnected from the rails of the associated section. Since back contact 25 of each track relay R is open, all of the control 110 relays P and Q are de-energized, and the supply of current to primary 14 of each transformer G is interrupted.

The trackway apparatus herein shown and described is particularly adapted for, though 115 in no way limited to, use in connection with train carried governing means arranged to give one indication when interrupted alternating current flows in the track rails and to give a different indication when the rails are 120 supplied with uninterrupted alternating current or with no current. Train carried governing means of this type is usually controlled by the currents in the trackway through the medium of receiving apparatus 125 130

carried on the train in advance of the forward axle. It follows that with apparatus of this type the source of train controlling current must always be connected with the 5 rails ahead of the train.

In explaining the operation of the apparatus, I will first assume that a westbound train enters section A—B. The presence of this train in this section causes signals S¹ 10 and S⁴ to indicate stop, but signal S⁶ indicates proceed. The presence of the train in section A—B also causes relay R^B to be open, thereby connecting the secondary 15 of transformer G^B with the rails of the section through contact 39. The closing of back contact 25 of relay R^B also causes control 20 relays P^A and Q^B to be intermittently operated. Contact 4—5 of circuit controller D⁶ is closed so that alternating current is supplied to primary 11 of transformer K^A 25 over back contact 43 of control relay P^A. Section A—B is therefore supplied with interrupted alternating current in advance of the train.

25 It should be noted that under these conditions interrupted alternating current is being supplied to primary 14 of transformer G^B over contact 4—5 of circuit controller D⁶ and that the secondary of this transformer 30 is connected directly in parallel with winding 7 of track relay R^B. But this relay is intended to be operated only by current supplied thereto from the transformer K located at the opposite end of the section. In order to prevent improper operation of the 35 relay R by current supplied thereto by transformer G^B, I reverse the connections of transformer G^B with respect to the connections of transformer K^A so that the relative 40 instantaneous polarity of the current supplied to winding 7 of relay R^B by transformer G^B is opposite to the relative instantaneous polarity of the current supplied to this winding by transformer K^A. The 45 tendency of the current supplied by transformer G^B therefore is to open relay R^B rather than close this relay.

I will next assume that the section to the 50 left of point A is occupied by a train. Signal S⁶ therefore indicates stop so that contact 4—6 of circuit controller D⁶ is closed. If, now, a westbound train enters section A—B, relays P^A and Q^B are operated as before, but back contact 43 of control relay P^A 55 is no longer included in the circuit for primary 11 of transformer K^A so that the alternating current supplied to the rails of section A—B in advance of the second train is uninterrupted. I will next assume that an 60 eastbound train occupies section A—B. The presence of this train in this section causes signals S¹ and S⁴ to indicate stop, but signal S³ indicates proceed. The train in section A—B causes the deenergization of 65 relay R^B, thereby connecting secondary 13

of transformer G^B with the rails of the section and causing control relays P^A and Q^B to be intermittently operated. Contact 4—5 of circuit controller D⁶ is closed so that alternating current is supplied to primary 14 70 of transformer G^B, over back contact 52 of control relay Q^B and back contact 25 of relay R^B. Under these conditions, therefore, interrupted alternating current is supplied to the rails of section A—B in advance of the train by transformer G^B. For the reasons pointed out above, this alternating current will not close relay R^B.

If section B—C is occupied by a second 75 eastbound train, signal S³ will indicate stop so that primary 14 of transformer G^B will be disconnected from transformer L^B, with the result that no alternating current will be supplied to the rails of section A—B in advance of the train in that section.

80 Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

95 1. Railway traffic controlling apparatus comprising a section of railway track over which traffic moves in both directions, and means for at times supplying both ends of said section with interrupted alternating current.

100 2. Railway traffic controlling apparatus comprising a railway track divided into sections over which traffic moves in both directions, and means effective when a section is occupied by a train moving in either direction and controlled by traffic conditions in advance of the train for supplying the rails of the section ahead of the train with interrupted alternating current.

105 3. Railway traffic controlling apparatus comprising a section of railway track over which traffic moves in both directions, and means effective when said section is occupied by a train moving in either direction and controlled by traffic conditions beyond said section and ahead of the train for supplying the rails of the section ahead of such train with interrupted alternating current.

110 4. Railway traffic controlling apparatus comprising a section of railway track over which traffic moves in both directions, means for normally supplying uninterrupted alternating current to one end of said section, means effective when such section is occupied by a train approaching said one end of the section and responsive to traffic conditions in advance of such train for supplying interrupted alternating current to the rails ahead of the train, and means effective

when the section is occupied by a train moving in the opposite direction for at times supplying the rails of the section ahead of the train with interrupted alternating current.

5. Railway traffic controlling apparatus

comprising a section of railway track over which traffic moves in both directions, two transformers one located adjacent each end 10 of said section for supplying current to the rails of the section, means for normally supplying uninterrupted alternating current to one of said transformers, means effective when such section is occupied by a train 15 moving in one direction and responsive to traffic conditions in advance of such train for supplying interrupted alternating current to said one transformer, and means effective when the section is occupied by a 20 train moving in the opposite direction for at times supplying the remaining transformer with interrupted alternating current.

6. Railway traffic controlling apparatus comprising a section of railway track over 25 which traffic moves in both directions, a first transformer having its secondary connected across the rails adjacent one end of said section, a first device controlled by traffic conditions for governing traffic leaving said 30 section at said one end, a track relay connected across the rails adjacent the other end of said section, a second transformer having its secondary connected across the rails adjacent said other end of the section in series 35 with a contact of said relay, a second device controlled by traffic conditions for controlling traffic leaving said section at said other end, means controlled by said first device for supplying the primary of said first 40 transformer with uninterrupted alternating current or with interrupted alternating current and means controlled by said second device for at times supplying the primary of said second transformer with interrupted 45 alternating current.

7. Railway traffic controlling apparatus comprising a section of railway track over which traffic moves in both directions, a first transformer having its secondary connected 50 across the rails adjacent the left-hand end of said section, a second transformer, means for connecting the secondary of said second transformer across the rails adjacent the right-hand end of the section, two normally 55 open control relays one located adjacent each end of the section and each arranged to alternately open and close its contacts when said section is occupied by a train, a first signal for controlling westbound traffic leaving said section, means controlled by said first signal and by one of said control relays for supplying alternating current to the primary of said first transformer, a second signal for controlling eastbound traffic leaving said section, and means controlled by

said second signal and by the remaining control relay for supplying alternating current to the primary of said second transformer.

8. Railway traffic controlling apparatus comprising a section of railway track, a first 70 transformer having its secondary connected across the rails of said section adjacent one end thereof, means for supplying alternating current to the primary of said first transformer, a track relay having one winding 75 connected with the rails of said section and a second winding constantly supplied with alternating current, a second transformer, means for connecting the secondary of said second transformer with the rails adjacent 80 the other end of said section, means for at times supplying interrupted alternating current to the primary of said second transformer, the secondaries of said two transformers being oppositely connected 85 with the rails of said stretch so that said relay may become energized by current from said first transformer but not from said second transformer.

9. Railway traffic controlling apparatus 90 comprising a section of railway track over which traffic moves in both directions, two normally de-energized control relays, means for intermittently operating both said control relays when said section is occupied by 95 a train, means controlled by one said control relay for at times supplying interrupted alternating current to the rails adjacent one end of the section, and means controlled by the other control relay for at times supplying interrupted alternating current to the rails adjacent the other end of the section.

10. Railway traffic controlling apparatus comprising a section of railway track over 100 which traffic moves in both directions, two normally de-energized control relays, means for intermittently operating both said control relays when said section is occupied by a train, means controlled by traffic conditions and including one of said control relays for 105 supplying uninterrupted alternating current or interrupted alternating current to the rails adjacent one end of the section, and means also controlled by traffic conditions and including the remaining control relay 110 for at times supplying interrupted alternating current to the rails adjacent the opposite end of the section.

11. Railway traffic controlling apparatus comprising a section of railway track over 115 which traffic moves in both directions, a track relay connected across the rails of the section, two normally de-energized control relays, means for intermittently operating both said control relays when said track relay is de-energized, means controlled by one of said control relays for at times supplying the rails adjacent one end of the section with uninterrupted alternating current or with 120 interrupted alternating current according 125 to

as such control relay is de-energized or is intermittently operated, means responsive to traffic conditions for at times removing said control relay from the control of such current, and means controlled by the remaining control relay for at times supplying the rails adjacent the opposite end of said section with interrupted alternating current.

12. Railway traffic controlling apparatus comprising a section of railway track over which traffic moves in both directions, a track relay connected with the rails adjacent one end of the section, means for normally supplying uninterrupted alternating current to the rails adjacent the other end of the section, and means controlled by said track relay for at times supplying interrupted alternating current to the rails adjacent one end or the other of said stretch in accordance with traffic conditions.

13. Railway traffic controlling apparatus comprising a section of railway track over which traffic moves in both directions, and means effective when said section is occupied by a train for at times supplying both ends of the section with interrupted alternating current.

14. Railway traffic controlling apparatus comprising a section of railway track over which traffic moves in both directions, and means effective when said section is occupied

by a train and responsive to traffic conditions for supplying both ends of said section with interrupted alternating current.

15. Railway traffic controlling apparatus comprising a section of railway track over which traffic moves in both directions, and means for at times supplying one end of said section with interrupted alternating current and for at other times supplying both ends of the section with interrupted alternating current.

16. Railway traffic controlling apparatus comprising a section of railway track over which traffic moves in both directions, means for normally supplying one end of the section with uninterrupted alternating current, means effective when said section is occupied by a train approaching such one end of the section and responsive to traffic conditions in advance of the train for periodically interrupting said current, means effective when said section is occupied by a train moving in the opposite direction for supplying interrupted alternating current to the rails ahead of such train, and means responsive to traffic conditions for at times discontinuing the supply of such last-mentioned current.

In testimony whereof I affix my signature.

HERBERT A. WALLACE.
